HYDRAULIC VALVE

Harold W. Darr, Minneapolis, Minn., assignor to Char-Lynn Co., Minneapolis, Minn., a corporation of Minnesota

Application December 31, 1954, Serial No. 33,774

Term of patent 14 years

(Cl. D78—1)

Fig. 1 is a view in perspective of a hydraulic valve showing my new design;

Fig. 2 is a view in top plan;

Fig. 3 is a view in side elevation;

Fig. 4 is a view in bottom plan; and

Fig. 5 is an end elevation as seen from the right to the left with respect to Fig. 3.

I claim:

The ornamental design for a hydraulic valve, as shown.
